APPARATUS FOR ATOMIZING LIQUIDS

Karl Flury, Adliswil, Switzerland, assignor to Defensor
A. G., Zurich, Switzerland

Application March 8, 1955, Serial No. 492,990

Claims priority, application Switzerland March 11, 1954

7 Claims. (Cl. 299—63)

The present invention relates to an improvement of the apparatus for atomizing liquids as disclosed in the Swiss Patents Nos. 257,663 and 285,473.

In those apparatuses, in order to form a fine mist (aerosol) the liquid led to at least one rotating surface is thrown by centrifugal action to an atomizing member provided and surrounded by the casing-jacket of the apparatus, this serving also as baffle and guide plate for the mist to be ejected.

In an apparatus of the aforementioned type, the invention essentially consists in that the casing-jacket, open at top and bottom, is circumferentially divided into two parts by an additional air inlet provided in the bottom part, both of which parts attached to the frame, the lower part carrying the motor system with the throwing system, while the upper part is designed as baffle and guide plate, at least in part, and carries at the outlet-opening a vertically adjustable collar.

Further features of the invention will appear from the claims, specification and accompanying drawing, which latter represents by pure way of example a preferred embodiment of the apparatus incorporating the invention.

In said annexed drawing:

Fig. 1 is an elevation and longitudinal section of the example of embodiment;

Fig. 2 is a diagrammatic representation and part-sectional view of the mounting of the thrower surfaces on the hub connected to the motor shaft.

Referring to the form of embodiment shown in Fig. 1, the apparatus includes a substantially pot-shaped casing 1a, 1b which stands on feet 2. Arranged in the longitudinal axis of said casing is an electric motor 3. The bottom end of its shaft 4 has removably attached to it a thrower system in the form of a battery 5 of plane discs with a suction pipe 6. The latter dips into a vessel 7 filled with the liquid to be atomized. Opposite the outer rims of the plane-disc battery formed by the thrower surfaces or discs 5, the apertured atomizing member 8 is arranged in the form of an annulus.

The arrangement and design of the aforesaid essential parts of the apparatus are as follows:

The casing-jacket 1a, 1b, open at top and bottom for air inlet and outlet, is circumferentially divided into two parts by an additional air inlet 9 in the lower part, both of which parts are attached to the feet 2 forming the frame, the lower part carrying the motor system and the thrower system, while the upper part 1a of said casing is designed, at least in part, as baffle and guide plate for the ejected mist and carries at the outlet-opening a vertically adjustable collar 10.

The lower part 1b of the casing is fixed by screws on the feet 2 of the frame. Said screws 11 secure at the same time a sheet metal deflector ring 12 to the lower casing part 1b which extends with a cylindrical portion parallel to the central axis of the apparatus and covers the air inlet 9. Consequently, the air entering the circumferential opening 9 is on the one hand directed through the inner wall of the upper casing part 1a and

2

on the other hand upwards by the outer surface of the ring 12. On the ring 12, the whole motor system with the thrower system is suspended in the following way:

The casing of motor 3 is connected through clips 13 and screws 14 to the motor shrouding, which comprises the two parts 15a and 15b. Fitted from below to the lower casing part 15a is the apertured atomizing member 8 in the form of a lamellar ring. Further, the upper casing part 15b may be put onto the lower part 15a and be secured, if necessary, by special means. Through the lower casing part 15a the motor system is thus firmly connected to the ring 12 seated on the lower casing-jacket part 1b, i. e. by hollow screw bolts 16 and spacer rings 16a. During operation of the apparatus, a considerable suction effect is produced through the disks 5 in close proximity to the lower end of shaft 4, by which suction effect the air is exhausted out of the casing 15a, 15b along the lower part of the shaft 4. To prevent the formation of a vacuum inside the casing and to prevent the suction of humid moist air through the upper aperture thereof, the hollow screw-bolts provide means for allowing dry air to flow into the casing 15a, 15b and for equalizing the pressure between the inner chamber of the motor and the inner space of the casing-jacket. The outer surface of the motor casing 15b and the inner wall of the upper casing-jacket part 1a constitute, together with the upper opening or collar 10, the guide plates of the mist ejection channel. The upper part 1a of the casing-jacket is by screws 17 mounted on the frame feet 2. The outer surface of the motor casing 15b and the inner wall of the upper casing-jacket part 1a preferably have unevennesses in the form of roughings, ribs, etc., which unevennesses essentially help to improve the quantity and quality of the aerosol and to make the mist very fine.

When the surfaces are so roughened, a thin fluid film may be readily formed thereon causing the impacting spray drops to merge immediately into a continuous film and to prevent the formation of larger drops which might unfavorably affect the air flow. The operating efficiency of the apparatus is thus greatly increased by the surface roughening.

The collar 10, axially slidably carried in the upper cylindrical portion of the casing-jacket 1a, has a bead 10a as stop for its lower end position, while said collar is withdrawable upwards and removable. The collar 10 is slotted lengthwise and snugly fits the cylindrical portion of the casing jacket 1a. The collar 10 is particularly adapted to direct the ejected mist to a great height, i. e. in the case of high rooms. Moreover, by the use of the collar 10 air turbulence is reduced and a substantially non-turbulent ejection can be obtained. The collar also serves to separate the larger mist particles in the space 18 formed between collar 10 and jacket 1a. Due to the flow of air from the opening 9 to the upper portion of the jacket, the spray produced on the spray ring 8 is forced against the curved outer surface of the motor casing 15b as it progresses upwardly to the outlet aperture in the upper part of the casing. Due to centrifugal action, the heavier water particles in the spray cannot follow the curvature of the path to the same extent as the lighter, smaller spray drops, and hence flow outwardly along the inner surface of casing-jacket 1a to finally impact on the external surface of the collar member 10 projecting into the casing 1a. Consequently, the adjustment of the fineness of mist for a certain motor performance may be obtained by vertical movement of the collar 10.

The motor shaft 4 has a vertically displaceable and adjustable propeller 19 arranged at its upper end which draws air through the air inlet aperture 9 and forces it out of the casing jacket through collar 10. Seated on

3

the related shaft portion there is moreover a socket 20 adapted to close the passageway into the casing 15.

Removably connected to the lower end of the shaft 4 by a screw 21, is a hub 22 having the thrower discs 5 arranged thereon. For this purpose the hub 22 has, say, six radial ribs 23 (Fig. 2) against the front edges 23a of which the inner rims of the discs 5 rest for centering and balancing them. By screws 24 (Fig. 1) which extend through corresponding bores 25 of the thrower discs 5, these are attached to the annular part 22a of the hub 22 and at the same time to the suction pipe 6. The radial ribs 23 of the thrower discs are not only adapted for centering and balancing them, but also serve as a centrifugal pump. Since the liquid sucked-in through the inlet 6 between the six radial ribs 23 passes out to the thrower discs 5, six liquid outlet zones appear on the discs 5. In order to distribute evenly over 360 degrees the liquid outlet interrupted circumferentially, the upper sides of the thrower discs 5 can be interrupted in their radial course by an annular ridge, which may consist of a round rib or hump 26, such as indicated as a modification to the upper disc 5 in Fig. 2.

The inlet pipe rotating with the thrower system may at its lower end be preferably provided with a transverse rib 6a acting as centrifugal pump in order to obtain a greater output. The increased quantity of liquid thereby entrained rather involves the risk of fouling the thrower system, for which reason the suction branch is at its lower end surrounded by a sieve 27 seated on a mount 28 being in turn detachably secured below at the lower casing-jacket part 1b in the manner shown in Fig. 1. Said sieve serves not only to prevent fouling of the system, but also to avoid turbulence in order to calm the liquid in the vessel 7. The mount 28 for the sieve 27 is designed so that also other appliances or attachments may be put thereon.

With the inlet 6 provision may be made for an electric heater, preferably in the shape of a heating coil encircling the sieve 27 and adapted to preheat the liquid in the container 7, thus further helping to increase the output of the apparatus.

What I claim is:

1. Apparatus for atomizing liquids and discharging the same in the form of an aerosol mist, comprising a casing, said casing having a discharge opening and an air inlet opening, a housing within and spaced from said casing to provide a passage between said casing and said housing, said casing and said housing being of such a configuration that said passage is curved and converges toward said discharge opening, means for moving air through said passage from said inlet opening to said discharge opening, atomizer means for introducing fluid particles to said moving air to form a mist therein, and a collar secured within said discharge opening and extending into said passage, said collar serving as a baffle to collect heavier particles in the mist which are unable to follow said curved passage due to the centrifugal effect occurring during curvilinear travel.

2. Apparatus for atomizing liquids and discharging the same in the form of an aerosol mist as defined in claim 1, wherein said collar is adjustably mounted within said discharge opening to provide means for controlling the size of the fluid particles emitted therefrom.

3. Apparatus for atomizing liquids and discharging the same in the form of an aerosol mist, comprising a casing, said casing having a discharge opening at the top thereof, a first intake opening at the bottom thereof and a second intake opening in the walls of said cas-

ing intermediate said discharge and said first intake openings, a vertical shaft in said casing, a motor for driving said shaft, a housing surrounding and enclosing said motor and spaced from said casing to provide a curved, converging passage through which air moves from said intake openings to said discharge opening, a propeller secured to the upper end of said shaft near said discharge opening and causing said movement of air through said passage, a fluid receptacle beneath said casing, a suction pipe connected to said shaft at the lower end thereof and projecting into said fluid receptacle, at least one distributor disk secured to and extending outwardly from the upper end of said suction pipe, a stationary disintegrator ring surrounding said distributor disk, said ring having a multiplicity of baffles spaced to provide passages therebetween through which liquid particles discharged from said distributor disk may pass, said second air intake opening being substantially opposite said disintegrator ring, a cylindrical deflector ring coaxial with said disintegrator ring, said deflector ring being secured by an air-tight seal at its lower edge to said casing and extending between said disintegrator ring and said second air intake opening, and a collar secured within said discharge opening and extending into said passage, said collar serving as a baffle to collect heavier particles in the mist which are unable to follow said curved passage due to the centrifugal effect occurring during curvilinear travel.

4. Apparatus for atomizing liquids and discharging the same in the form of an aerosol mist as defined in claim 3 including means for conveying into said motor housing dry air from said second air inlet opening.

5. Apparatus for atomizing liquids and discharging the same in the form of an aerosol mist as defined in claim 4 wherein said conveying means comprise hollow bolts securing said motor housing to said ring wall.

6. Apparatus for atomizing liquids and distributing the same in the form of an aerosol mist as defined in claim 3 wherein the surfaces of said casing and said housing contacted by said mist are roughened to facilitate the wetting of said surfaces and to prevent the forming of large fluid droplets thereon.

7. Apparatus for atomizing liquids and distributing the same in the form of an aerosol mist as defined in claim 3 wherein said means for connecting said disks and said suction pipe to said shaft comprise a hub member secured to the lower end of said shaft, said hub member having radial ribs projecting therefrom and serving as blades of a centrifugal pump, said disks having apertures through the center thereof to allow said disks to be mounted and centered in stacked relation on said ribs, and means for securing the uppermost portion of said suction pipe to the under surface of said lowermost disk.
